UNITED STATES PATENT OFFICE

TORSTEN ADIL LUNDELL AND TORBERN LAURENT, OF STOCKHOLM, SWEDEN, ASSIGNEES TO TELEFONAKTIEBOLAGET L. M. ERICSSON, OF STOCKHOLM, SWEDEN, A COMPANY OF SWEDEN

TELEPHONE SYSTEM

Application filed April 13, 1931, Serial No. 529,812, and in Sweden January 22, 1929.

The present invention relates to automatic telephone systems. More particularly it relates to such installations in which selector impulses are to be sent over lines including 5 intermediate repeaters.

With a growing automatization of telephone systems it has become desirable to be able to send impulses for the control of selectors over long distance lines, coil-loaded 10 cables, long coil-loaded junction lines between local exchanges, etc. When using usual direct current impulses or alternating current impulses of low frequency considerable technical difficulties arise and it has 15 therefore been proposed to use voice-frequency alternating currents, by way of example currents having a frequency of 500 cycles, for transmitting selector impulses over long lines. The use of voice-frequency 20 alternating currents for transmitting selector impulses over long distance lines or the like involves considerable advantages since such lines generally are constructed to transmit voice-frequency alternating currents 25 with a minimum of damping and further generally include intermediate repeaters, which amplify passing voice-frequency currents but which, on the other hand, not at all or only with difficulty let through currents 30 of a higher or a lower frequency.

A receiver for receiving such signals must, however, be selective in order not to be actuated by speech currents during the conversation or by disturbance currents. However, this selectivity of the receiver cannot 35 be obtained without simultaneously introducing a certain inertia whereby the reception of rapid selector impulses is made more difficult.

According to the present invention this difficulty is eliminated thereby that the receiver is normally in a selective condition, being unsensitive to talking oscillations in 40 general and particularly also to such talking oscillations which by chance come within the signal frequency range, but, on the other hand, reacting for call signals or the like of 45 comparatively long duration, the receiver being adapted, upon receiving such signals, 50 to be shifted to a less selective or unselective

condition, thereby becoming capable of receiving rapid selector impulses. After completed selecting operation the receiver is again shifted to normal selectivity so that it is prepared, during the conversation, to receive the clearing signal. 55

The invention will be more closely described with reference to the accompanying drawings in which Figures 1, 2 and 3 show different embodiments of receivers adapted 60 to receive selector impulses as well as signals and provided with shifting means for shifting from a selective condition to a less selective or an unselective condition, and vice versa. 65

In Figure 1 a voice-frequency generator 2, by way of example a valve generator, buzzer or the like, is connected to the sending end of the line 1. The current supplied by the generator is controlled by an impulse sender 3, by way of example a finger disc. To the receiving end of the line is connected an impulse receiver 4, including a rectifying device in which the alternating current impulses are transformed to direct 70 current impulses. The latter impulses in turn actuate over a selectively acting device a sequence switch 6 or selectors connected thereto, said selectors being diagrammatically represented by a contact arm 7. Said 75

selective device, which in the embodiment according to Figure 1 is selective with respect to the duration of the signals, comprises a slow acting relay 40 and a co-operating relay 5, of which relays the former is normally connected to the impulse receiver 4 over a switch consisting of the contact set of a relay 41. The relay 5, on the other hand, is normally disconnected 80 from the circuit and adapted to be connected to the impulse receiver 4 in place of the relay 40 upon said switch being shifted at the energization of the relay 41. A voice-frequency call signal of the required duration is transformed in the impulse receiver 4 to a direct current impulse of corresponding duration, the duration being sufficient 85 to bring about the energization of the relay 40 whereby the sequence switch 6 is actuated and set in a certain position in which 90

100

it closes the circuit through the relay 41 which attracts its armature, disconnecting the relay 40 and connecting the relay 5 into circuit. Consequently the more rapid selector impulses hereafter incoming will actuate the latter relay which thus repeats the selector impulses for setting the selector. As soon as the desired connection is established the current through the relay 41 is interrupted due to the shifting of the sequence switch, the shifting device returns to its normal condition, the relay 5 is disconnected from the circuit and the relay 40 again connected to the impulse receiver 4. The device is thus again shifted to a selective condition, whereby disturbance currents of short duration are prevented from actuating the selectors.

Figure 2 shows a similar arrangement. The two relays 40 and 5 in Figure 1 alternatively connected into circuit are here replaced by a single relay provided with two windings 42, 43 and adapted to be shifted from a slow-acting to a quick-acting condition by removing a normally existing short circuit on the winding 43. The winding 42 is permanently connected to the impulse receiver 4. The short circuiting of the winding 43 takes place at a normally closed contact of a relay 44 corresponding to the relay 41 in Figure 1 and connected to the sequence switch in the same manner as said relay. As the relay 42, 43 is normally slow-acting similarly to the relay 40 in Figure 1 short signals, for instance disturbance currents, cannot actuate the same. If, on the other hand, a call signal of comparatively long duration is received the relay 42, 43 attracts its armature, whereby the sequence switch is actuated and in the same manner as in the above described embodiment closes the circuit through the relay 44 which is energized, whereby the short circuit of the winding 43 is removed and the relay 42, 43 shifted from a slow-acting condition to a quick-acting condition, thus becoming capable of responding to the selector impulses. After the completion of the selecting operation the relay 44 is de-energized and the coil 43 is again short-circuited, the relay 42, 43 becoming again slow-acting and thus selective.

Figure 3 shows an application of the invention in conjunction with a receiving device of the kind described in the Swedish Patent No. 66,958. In this case the impulse receiver 4 consists of said known receiving device which is normally selective with respect to frequency and adapted to receive signalling currents within a certain comparatively limited frequency range but which is, on the other hand, normally unsusceptible to other signalling currents. To the output side of the impulse receiver is connected a direct current relay 5, the con-

tact set of which may be assumed to be connected to a suitable signalling device and also to the sequence switch 6, as in Figure 1. The winding of the relay 5 is included in the anode circuit of an electron valve 8. The grid circuit of said valve comprises two branch circuits 9, 10 each including the secondary winding of a transformer 11 and 12 respectively, the primary windings of which are series-connected in the anode circuit of an amplifier valve 13, the grid circuit of which is connected to the receiving end of the line 1 through the transformer 14. Through a battery 15 the valve 13 receives a negative grid biasing voltage of such a magnitude that the valve acts only as an amplifier. A battery 16 supplies current to the anode circuit of both valves 8 and 13. The primary windings of the transformers 11, 12 are each provided with a resonance shunt 17 and 18 respectively, tuned to the frequency of the signalling current. As previously mentioned the same frequency may be used also for the selector impulses. The shunt 17 is arranged for voltage resonance and includes an inductance and a capacity connected in parallel therewith, whereas the shunt 18 is arranged for current resonance and includes an inductance and a capacity in series. The anode circuit of the valve 15 forms a filter circuit with two series connected filters 17 and 18. The filter 17 transmits to the branch circuit 9 only currents within the frequency range of the signalling currents. The filter 18, on the other hand, transmits to the branch circuit 10 currents which lie outside the frequency range of the signalling currents, thus talking currents in general, whereas the signalling currents are substantially blocked from the circuit 10 by the shunt 18 acting as a short circuit for said currents.

When a wave-train of talking currents, for instance also including talking oscillations of signalling frequency or approximately of signalling frequency, are received from the line over the transformer 14 and the amplifier 13 the condenser in the shunt 17 will to begin with act as a short circuit, whereas the shunt 18 acts as a high resistance. For this reason currents of signalling frequency and short duration will be transmitted to the circuit 10 together with the other currents but will, on the other hand, leave the circuit 9 substantially unaffected. With regard to the signalling frequencies the conditions in the shunt will be reversed as in this case the shunt 17, as previously mentioned, will offer a high resistance to the signalling currents as soon as a stationary condition of oscillations has been established, whereas the shunt 18 forms a short circuit. The transformer 12 together with the shunt 18 and the branch circuit 10 thus form a blocking device which controls

the signal receiver in such a way that the latter becomes unsensitive to the talking currents including the oscillations included therein lying inside the signal frequency range.

Each branch circuit 9 and 10 respectively includes in series with the secondary winding of the transformer 11 and 12 respectively a glow lamp 19 and 20 respectively 10 having a built-in resistance 21 and 22 respectively. In place of glow lamps other similar discharge devices having an independent discharge may be used. Upon each glow lamp is impressed a direct current 15 voltage from a battery 26 and 27 respectively, which voltage, however, alone is unsufficient to make the lamp glow. Thus the glow lamp 19, 20 normally acts as an interruption in the secondary circuits of the 20 transformers 11, 12.

The grid circuit of the valve 8 comprises, in addition to the branch circuits 9, 10, also a third branch 23 in which is included a grid leak 24 shunted with a condenser 25. 25 Through the battery 26 and another battery 26' the grid of the valve 8 obtains a negative grid biasing voltage of such a value that the anode current is practically zero in the normal condition of the receiving device. 30 Voltages induced in the circuits 9, 10 through signalling currents and other alternating currents incoming from the outside are superposed upon the direct current voltages impressed upon the glow lamps 19, 20 35 and may, if sufficiently strong, bring the corresponding glow lamp to glow, whereby a conducting path is established through the lamp. When the lamp 19 is brought to glow through an incoming signalling current the grid of the valve 8 is connected to the positive pole of the battery 26, the upper coating of the condenser 25 then receiving a positive charge. The grid voltage of the valve 8 is thus increased in a positive direction 40 which results in that a current passes through the winding of the relay 5 bringing the signalling device into operation. When the signalling current has ceased the condenser 25 is discharged through the grid leak 24 and the valve 8 is restored to its 45 normal position with currentless anode circuit.

If currents having another frequency than the signalling frequency and, for instance, including only short impulses of signalling frequency are received from the line only the glow lamp 26 is made to glow, the upper coating of the condenser 23 then receiving a negative charge from the battery 50 27. The anode circuit of the valve 8 thus remains currentless. If under this condition talking currents having frequencies capable of bringing the signalling device into operation should enter the receiver also 55 the glow lamp 19 is made operative supply-

ing a positive charge to the condenser 25. It has been found, however, that in speech the negative charge is favoured to such an extent as compared with the positive one that the latter will never be predominant. 70 This result depends substantially thereupon that the condenser is discharged comparatively slowly through the leak 24. Its negative charge will therefore be maintained until other frequencies than signalling frequencies are again predominant, when the condenser 25 is again negatively charged. The condenser 25 should therefore preferably have such a capacity that it may be charged by means of a small amount of 75 energy and the leak 24 should have such a resistance that one obtains the slow discharge of the condenser required for safe operation of the device.

The arrangement according to Figure 3 80 has the further advantage that disturbance currents, which usually have only a small energy, do not influence the signal receiver for the reason that weak currents are unable to bring the glow lamps to glow.

As will be clear from the foregoing the arrangement is very selective wherefore the relay 5 will be unaffected not only by currents outside the signal frequency range but also, on account of the inertia required for 90 obtaining the selectivity, also for very short impulses of signalling frequency. To render possible the reception of rapid selector impulses by means of this special receiver the sequence switch 6 is provided with a 100 special ring of contacts comprising two oppositely disposed contacts 29 which, upon the sequence switch being shifted through the call signal, are mutually interconnected and close a circuit through a relay 30 controlling two contacts 31, 32, of which the former is included in the shunt over the primary winding of the transformer 11 in series with the filter 17 and normally closing the shunt, whereas the other contact 32 is adapted to short-circuit the primary winding of the transformer 12 when the relay is energized, whereby the blocking device is thus made inoperative. The receiver is thereby shifted to a condition in 110 which it is more quick acting than before and is now prepared to receive the rapid selector impulses which over the transformer 14, the amplifier 13 and the transformer 11 are transmitted to the circuit 9 which rectifies the same and supplies the rectified voltage impulses to the condenser 25. The valve 8 will now be actuated in the same manner as when pure signalling impulses are received, as previously described. The selector impulses will be repeated by the relay 5, through the contact circuit of which they are supplied to the selector mechanism. After completed selecting operation the circuit for the relay 30 is interrupted by a 120 125 130

further shifting of the sequence switch 6 whereby the shunt 17 is again closed and the short circuit of the transformer 12 removed. The receiver is thereby restored to 5 its original selective condition, in which it should remain during the following conversation in order to be prepared to receive the clearing signal.

The invention may also be applied to 10 wireless transmission of selector impulses with the aid of a high-frequency carrier wave. Instead of making the signal receiver selective with respect to the frequency or to the duration of the signal one may, in 15 a manner known per se, make the same selective with respect to the amplitude of the signalling current.

We claim:—

1. In a telephone system in combination, a 20 transmission line, means for transmitting signalling currents of voice frequency over said line, a signal receiver, means associated with said receiver and responsive to signals of predetermined minimum length for 25 changing the condition of said receiver from a higher to a lower degree of selectivity so as to make the receiver responsive to rapid signal impulses.

2. In a telephone system in combination, a 20 transmission line, means for transmitting signalling currents of voice frequency over said line, a signal receiver, means associated with said receiver and responsive to signals of predetermined minimum length for 35 changing the condition of said receiver from a higher to a lower degree of selectivity, a selector arranged under the control of said receiver, and means under the control of the selector for re-establishing the normal high 40 selective condition of the receiver.

3. In a telephone system in combination, a transmission line, means for transmitting signalling currents of voice frequency over said line, a signal receiver normally responsive to signals of predetermined minimum length, a selector arranged under the control of said receiver, means under the control of the selector for shifting the receiver from a more selective to a less selective condition, and other means under the control of said selector for re-establishing the normal high 70 75 selectivity of the receiver.

4. A device for receiving voice frequency signals in telephone plants comprising a signal receiver normally responsive to signals of predetermined minimum length, a selector arranged under the control of said receiver, means under the control of the selector for shifting the receiver from a more selective to a less selective condition, and other means under the control of the selector for re-establishing the normal high 80 85 selectivity of the receiver.

5. A device for receiving voice frequency signals in telephone plants comprising a rectifying device, a signal receiver normally responsive to rectified signals of predetermined minimum length, a selector arranged under the control of said receiver, means under the control of the selector for shifting the receiver from a more selective to a less selective condition, and other means under the control of the selector for re-establishing the normal high 90 95 selectivity of the receiver.
